UNITED STATES PATENT OFFICE

2,216,583

CIRCUIT BREAKER

Kuno Bauerschmidt, Karlsorst, Germany, assignor to General Electric Company, a corporation of New York

Application January 2, 1940, Serial No. 312,109
In Germany January 10, 1939

9 Claims. (Cl. 200—144)

The present invention relates to electric circuit breakers, and more particularly to improvements in circuit breakers of the gas blast type.

It is an object of this invention to provide an improved construction in gas blast switches which is characterized by its compact and rugged construction, ease of manufacture and assembly and low cost of production.

It is another object of the invention to provide an improved circuit breaker of the above type particularly adapted for multiphase installations and which requires little space for expanding and cooling effectively the heated gases exhausted from the arc chamber of the breaker.

Further objects and advantages will become apparent as the following description proceeds, reference being had to the accompanying drawing in which Fig. 1 is an elevational view in section of a circuit breaker embodying the invention; Fig. 2 is an end elevational view of the breaker of Fig. 1; Fig. 3 is an elevational view partially in section of a modification; Fig. 4 is an end elevational view of another modification of the breaker arrangement of Fig. 1; Fig. 5 is a sectional view taken along the line 5—5 of Fig. 4; and Fig. 6 is a sectional view taken along the line 6—6 of Fig. 4.

Referring to the drawing, I have shown my invention embodied in a three-pole circuit breaker of the expulsion type comprising a plurality of circuit-interrupting units illustrated generally by numeral 10. Each of the units is preferably of identical construction and comprises an arc-confining structure 11, preferably in the form of a cylindrical sleeve or tube of suitable gas-emitting material. The fixed contact 12 is mounted at one end of the tube and secured in position by a metal cap 13 which may conveniently form one terminal of the breaker. The cap is secured to the tube in any suitable manner, for example, by a screw-threaded connection (not shown). A movable contact rod 14 is arranged to enter the open end of the tube 11 and engage the fixed contact 12 in the closed circuit position of the breaker. The contact 14 slides in a suitable sleeve contact 15 which is electrically connected to the other terminal of the breaker (not shown). For the purposes of simplification of the drawing, the operating mechanism, which may be of any suitable construction, has not been illustrated.

In accordance with the present invention the arc-confining structure or tube 11 is supported from a plate of insulating material 16 by a hollow open-ended chamber 17. The arc-confining tube

is received in aligned openings formed in the walls of the chamber 17 and is provided intermediate its ends with passages 18 which communicate with the interior of the chamber 17 and provide for the escape of the highly heated and ionized gases which are formed within the tube 11 during the circuit-interrupting operation of the breaker. In order effectively to cool the gases exhausted from the passage 18 the chamber 17 may to advantage be formed of material having good heat transfer properties, such as metal. The use of a heat-dissipating section in the path of the gases before they are expanded is very effective since the gases are at their highest temperature at this point. The use of a conducting chamber increases the insulation problems however and in breakers for certain applications it may be preferable to construct the chamber 17 of insulating material. The passages 18 are positioned in the walls of the tube 11 at such a distance from the fixed contact that they are uncovered during opening movement of the movable contact 14 after the separation of the fixed and movable contacts has proceeded far enough to extinguish a heavy current arc.

In accordance with another feature of my invention the chambers in which the exhaust gases are expanded are mounted one inside the other and are constructed to form a support for the interrupting units. In the drawing I have shown my invention embodied in a three-pole circuit breaker in which the insulating plate 16 forms a support for the interrupting units of each pole and also forms a header for the expansion chambers 20, 21, and 22. The expansion chambers are preferably made from tubes of insulating material which are mounted concentrically on the header 16 and each is arranged to communicate individually with the open end of a chamber 17 connected to a different one of the interrupting units. The expansion chambers are each provided with a muffler 23 in accordance with the well-known practice. As illustrated in Fig. 1 of the drawing, the breaker assembly is supported by the inner expansion chamber 22 from a suitable support 24 by means of a clamping ring 25 which may be secured to the tube 23 and support 24 in any suitable manner. Each of the expansion chambers 20, 21, and 22 are of a different length to provide for exhausting the heated gases from the structure at spaced points along its length.

In the operation of the breaker, an arc is drawn between the relatively movable contacts during

their separating movement. The arc acts upon the walls of the tube 11 to liberate arc-extinguishing gas which is dependent, among other things, upon the magnitude of the current being interrupted. When the current is large, the arc is interrupted when there is a relatively short separation of the relatively movable contacts and the passages 18 are arranged to exhaust these highly heated gases into the chamber 17 and from 10 there to the expansion chamber associated therewith. When the current being interrupted is small the arc is not extinguished until a greater separation of the contacts has taken place but, in these cases, the gases are much less highly 15 heated and may be safely exhausted to the atmosphere through the open end of the arc-confining tube 11.

In Fig. 3 I have shown my invention embodied in a modified circuit breaker construction which 20 is very similar to that described in connection with Figs. 1 and 2. In the construction shown in Fig. 3 the outer expansion chamber 20 is made longer than the other expansion chambers and is secured to a longitudinally extending conduit 25 20 which may be arranged to receive the exhaust gases from a plurality of circuit breaker units of a complete installation. This construction totally encloses the exhaust gases which may be exhausted from the end of the building in which 30 the switches are housed so that the possibility of flame being emitted in the vicinity of the breaker structure under severe operating conditions is eliminated. Using the larger expansion chamber as a support also provides a more rugged 35 and durable structure.

The present invention is not limited to a construction in which all of the expansion chambers are concentrically arranged, and in Figs. 4, 5, and 6 I have illustrated a modified structure embodying certain features of my invention. 40 In the modified construction the interrupting units are supported from a conduit 28 by the outer blast chamber 26 in the same manner as that described in connection with Fig. 3. The inner 45 expansion chambers, however, are arranged side by side within the outer expansion chamber.

The constructions described above have numerous advantages from a manufacturing and installation standpoint. The concentric arrangement of the expansion chambers, one of which forms a support for the circuit-interrupting units, provides a very compact assembly 50 which requires a minimum amount of space for a breaker of given voltage and current rating and eliminates the supporting bushings normally 55 required to mount the breaker. The chamber 17 which surrounds the arc-confining tube 11 may be readily formed of metal with the present construction and when so formed is very effective 60 to dissipate the heat carried by gases exhausted through the intermediate passage 18 when a high current arc is interrupted. The construction also provides easy access to the parts of the switch which require frequent inspection and occasional renewal such as the contact members and the arc-confining tube 11.

While the present invention is particularly useful in connection with gas expulsion-type interrupters, it will be apparent that many features thereof are applicable to other types of circuit interrupters, and I intend in the appended 70 claims to cover all modifications falling within the spirit and scope of my invention.

What I claim as new and desire to secure by 75 Letters Patent of the United States, is:

1. A circuit breaker comprising in combination a circuit-interrupting unit including a hollow arc-confining structure having an exhaust passage intermediate its ends and relatively movable contacts separable to draw an arc within said structure, an expansion chamber having an exhaust opening, and means communicating with said expansion chamber and said exhaust passage for supporting said interrupting unit outside said expansion chamber and for conducting exhaust gases from said interrupting unit to said expansion chamber. 5

2. A circuit breaker comprising in combination a circuit interrupting unit including an elongated hollow arc-confining structure having an exhaust 15 passage in a side wall thereof and relatively movable contacts separable to draw an arc within said structure, a support, an expansion chamber secured on said support, and means forming a conduit communicating with said exhaust passage and said expansion chamber for supporting 20 said circuit-interrupting unit outside of said expansion chamber.

3. A circuit breaker comprising in combination a circuit-interrupting unit including an elongated 25 hollow arc-confining structure having an exhaust passage in a side wall thereof and relatively movable contacts separable to draw an arc within said structure, a support, a tubular expansion chamber secured on said support, a hollow member 30 having an opening in a wall thereof communicating with said expansion chamber, said hollow member also having aligned openings in the spaced walls thereof in which said elongated arc-confining structure is received 35 whereby said interrupting unit is supported outside of said expansion chamber and the gases exhaust from said intermediate exhaust passage are conducted to said expansion chamber.

4. A multipole circuit breaker comprising in 40 combination a plurality of circuit-interrupting units each including an arc-confining structure and relatively movable contacts separable to draw an arc within said structure, a plurality 45 of expansion chambers mounted one within the other, and means for supporting said circuit-interrupting units in insulated relation on the outside of said expansion chambers and for conducting exhaust gases from the arc-confining structure of each of said interrupting units to 50 a different one of said expansion chambers.

5. A multiple circuit breaker comprising in combination a plurality of circuit-interrupting units each including an arc-confining structure and relatively movable contacts separable to 55 draw an arc within said structure, a plurality of concentrically mounted expansion chambers, and means for supporting said circuit-interrupting units in insulated relation on the outside of said expansion chambers, and means for conducting exhaust gases from the arc-confining structure of each of said interrupting units to 60 a different one of said expansion chambers.

6. A multiple circuit breaker comprising in combination a plurality of circuit-interrupting 65 units each including a hollow arc-confining structure having an exhaust passage intermediate its ends and relatively movable contacts separable to draw an arc within said structure, a plurality 70 of expansion chambers mounted in concentric relation and each having an exhaust opening, a plurality of intermediate chambers each having an opening communicating with a different one of said expansion chambers, each of said intermediate chambers being constructed 75

and arranged to support one of said interrupting units outside of said expansion chambers and to conduct exhaust gases from the exhaust passage thereof to one of said expansion chambers.

5. A multipole circuit breaker comprising in combination a plurality of circuit-interrupting units each including an arc-confining structure and relatively movable contacts separable to draw an arc within said structure, a supporting member, a plurality of expansion chambers of varying lengths secured together and mounted one within the other, the longer of said expansion chambers being connected to and supported by said member, and means for supporting each of said circuit-interrupting units outside of said expansion chambers and for conducting exhaust gases from the arc-confining structure of each of said interrupting units to a different one of said expansion chambers.

10. A circuit breaker comprising in combination, a support, a plurality of concentrically arranged expansion chambers on said support, a header closing one end of said expansion cham-

bers, a plurality of circuit-interrupting units each including a hollow arc-confining structure having an exhaust passage intermediate its ends and relatively movable contacts separable to draw an arc within said structure, a plurality of hollow open-ended members mounted in spaced relation on said header and each having its open end communicating with a different one of said expansion chambers, each of said members being constructed and arranged to support one of said interrupting units on the outside of said expansion chambers and to conduct exhaust gases from the intermediate exhaust passage thereof to one of said expansion chambers.

15. A multipole circuit breaker comprising a plurality of expansion chambers, means for mounting said chambers in concentric relation, a plurality of circuit-interrupting units mounted outside of said expansion chambers, and means for conducting exhaust gases from each of said circuit-interrupting units to a different one of said expansion chambers.

KUNO BAUERSCHMIDT.
